CANOPY

Jimmie L. Jones, Salt Lake City, Utah, assignor to Ute Indian Tribe of the Uintah and Ouray Reservation, Uintah County, Utah

Filed May 2, 1972, Ser. No. 249,748

Term of patent 14 years

Int. Cl. D25—03

U.S. Cl. D13—1 D

FIG. 1 is a reflected plan view, partly in section, on the line 1—1 in FIG. 2;

FIG. 2 is a side elevation, partly in section, on the line 2—2 in FIG. 1; and

FIG. 3 is a cross section on the line 3—3 in FIG. 2.
I claim:

The ornamental design for a canopy, substantially as shown.
